CLAIM

The ornamental design for a locking cap for prosthetic liners as shown and described.

DESCRIPTION

FIG. 1 is a top view of the locking cap for prosthetic liners; FIG. 2 is a rotated top view of the locking cap for prosthetic liners;

FIG. 3 is a bottom view of the locking cap for prosthetic liners;

FIG. 4 is a side view of the locking cap for prosthetic liners; FIG. 5 is a side view of the locking cap for prosthetic liners;

FIG. 6 is a side view of the locking cap for prosthetic liners engaged with a prosthetic liner; and,

FIG. 7 is a bottom view of the locking cap for prosthetic liners engaged with a prosthetic liner.

The broken lines shown in the drawings are included for the purpose of illustrating portions of the locking cap for prosthetic liners and form no part of the claimed design.
